UNITED STATES PATENT OFFICE.

PETER N. PETERSEN, OF NEW YORK, N. Y.

FORM FOR CONCRETE WALL CONSTRUCTION.

Application filed April 25, 1925. Serial No. 25,781.

The invention relates to improvements in forms for cement wall construction and has for its object to provide an exceedingly simple and inexpensive apparatus whereby the 5 forms or mold boards are rigidly held against the expansion efforts of the concrete when the concrete is being poured into the forms.

The advantages and simplicity of the construction will be brought out in the following specification and illustrated in the accompanying drawings, forming a part thereof:

Referring to said drawings:

15 Fig. 1 is a side elevation,

Fig. 2 is a sectional view, on a larger scale, taken on the line 2—2 of Fig. 1, and

Fig. 3 is a sectional detail view taken on the line 3—3 of Fig. 2.

20 The reference numeral 5 denotes the longitudinal mold boards, which, as illustrated, are arranged in two parallel rows. Pairs of upright supports 6 are placed on the outer sides of the mold boards and at opposite disposed sides thereof.

25 Pairs of members 7 are secured to the outer sides of the upright supports 6. These members 7 may be in the form of cleats, or preferably in the form as in the drawings. The members 7 are secured in pairs to the upright supports 6 and are spaced apart slightly as indicated at 8 in Fig. 1.

30 Passing through the space 8 and extending from one pair of members 7 on one side of the mold boards to the pair on the opposite side are tie members 9. The tie members 9 are preferably made of a continuous piece of strong wire, the ends of which are 35 twisted together at 10, thus forming a loop. The length of these looped tie members depends upon the width of the wall that is to be built. The mold boards 5 may be notched out as indicated at 11 in Fig. 3 for the 40 passage of the tie members 9 or the boards may be slightly separated where the tie members pass.

45 The tie members 9 are made of a sufficient length so that a small portion of both ends 50 will project beyond the members 7, thus

forming eyes for the accommodation of anchorage pins 12. These anchorage pins are made of substantially heavy material, semi-circular in cross section and are bent so as to form two legs 13 and 14, at approximately right angles to each other.

55 The longer legs 13 of the anchorage pins pass through the looped portions of the tie members and the flattened parts of the pins bear against the members 7 at opposite outer sides of the mold boards, so that, when the concrete is being poured the mold boards are rigidly held against the lateral expansion due to the great pressure of the concrete. The shorter legs 14 of the anchorage 60 pins rest on the top sides of the higher of the two members 7 so that in case the forms should loosen slightly before the concrete is poured there would be no probability of the pin dropping from its position. If 65 thought necessary, a hole could be bored in the shorter leg 14 to accommodate a spike which could be driven into the upper of the horizontal members 7. This would maintain the pin firmly in position. Under ordinary circumstances this would not be required, however.

70 After the concrete has been poured and allowed to set the anchorage pins are removed and the forms taken down. The 75 looped exposed ends of the tie members sticking out beyond the finished wall are snipped off as closely as may be desired and the remainder of the tie member stays in the wall. The heavier longitudinal reinforcements could also be readily attached to the tie members and thus supported prior to pouring the concrete.

75 From the foregoing it is thought the manner of using and practicing the invention 80 will be generally understood. Changes in details of construction that would suggest themselves to anyone skilled in the art might be made without departing from the spirit of the invention or the scope of the appended claim.

85 What I desire to claim as new is:

90 Apparatus for construction of concrete walls, comprising two rows of longitudinally extending mold boards, upright sup- 95

ports for the boards, pairs of horizontal boards secured to the upright supports, looped tie members extending through the mould boards and between and beyond the 5 oppositely disposed pairs of horizontal boards, and anchorage pins flat at the inside and having two legs, one to pass

through the ends of the loops and the other to rest on the horizontal boards on which it is prevented from turning and falling out 10 by the flattened side abutting the sides of the horizontal boards.

PETER N. PETERSEN.
